CHILD'S TOILET SEAT ASSEMBLY

E. Burton Benjamin, Highland Park, Ill., assignor to
Loma Industries, Fort Worth, Tex., a corporation of
Texas

Filed May 24, 1965, Ser. No. 85,416

Term of patent 14 years

(Cl. D4—5)

FIGURE 1 is a front perspective view of the child's toilet seat assembly embodying my invention;

FIGURE 2 is a top plan view of my invention;

FIGURE 3 is a front elevational view of my invention;

FIGURE 4 is a left side elevational view of my invention;

FIGURE 5 is a rear elevational view of my invention;

FIGURE 6 is a bottom plan view of my invention;

FIGURE 7 is a sectional view taken along line 7-7 of FIGURE 2; and

FIGURE 8 is a sectional view taken along line 8-8 of FIGURE 2.

The supporting strap, shown in FIG. 1, is omitted in FIGS. 2 through 8 for convenience of illustration only.

I claim:

The ornamental design for a child's toilet seat assembly as shown and described.
